UNITED STATES PATENT OFFICE.

THOMAS G. PIHLFELDT AND FELIX C. HARTUNG, OF CHICAGO, ILLINOIS.

OIL-CUP.

1,350,566.

Specification of Letters Patent. Patented Aug. 24, 1920.

Application filed December 28, 1918. Serial No. 268,648.

To all whom it may concern:

Be it known that we, THOMAS G. PIHLFELDT, a citizen of the United States, and FELIX C. HARTUNG, a subject of Great Britain, both residing at Chicago, in the county of Cook and State of Illinois, have invented a new and useful Improvement in Oil-Cups, of which the following is a specification.

10 This invention relates to oil-cups and more particularly to the type of oil-cups wherein means are provided for forcibly ejecting oil from the cup into the bearing to which it is attached and also for maintaining a reservoir of oil for further feeding of the bearing.

The invention is shown in a preferred embodiment in the accompanying drawings in two figures, in which—

20 Figure 1 is a longitudinal section through the device, and Fig. 2 an elevation of the device from the end upon which the nipple is formed.

In the embodiment shown in the drawing, 25 the oil-cup comprises a main body portion 5 to which is rigidly attached the bored nipple 6, which may be threaded as shown at 7, or otherwise adapted for attachment to a bearing.

30 Within the body portion 5 is fitted a movable piston 8 which we prefer to shape as a cup-piston, as shown in Fig. 1 of the drawings. Below the piston 8 is placed a permeable membrane 9 also fitted to the interior of the body portion 5 and movable therein. This permeable membrane may suitably be constructed of a fabric material, such as felt. A suitable perforation, such as the small opening 10, passes through the 35 lower portion of the piston 8 to permit passage of oil therethrough, and, if desired, a wick of textile material 11, or other like device to control the flow of oil from the rear of the piston to its face, may be provided. Below the permeable membrane 9, 40 a coiled spring 12 is provided which rests against the constricted portion 13 of the body of the cup and exerts its force against the permeable membrane 9 to move it and 45 the piston 8 outwardly.

The cup is provided with a fitted cap 14 to which is pivotally attached by any suitable means, such as the stud 15 containing an eye 16 within the cap, a link 17. This 55 link 17 is fixed, for example, by soldering, to a ball 18 which may normally seat in a

central opening 19 provided in the face of the piston 8. To the opposite point on this ball is fixed a hook 21 in which engages the hooked end of a spiral spring 22 which extends into the bore of the nipple. An opening 20 is centrally provided in the permeable membrane 9 directly beneath the opening 19 in the piston 8 to permit of free movement of the spring 22 and its attachment means.

The lower end of the spring 22 is attached to the device by a suitable swivel mounting, for example, a rotatable washer 23 seated in an enlargement 24 of the bore of the nipple. The central portion of this washer may be struck up as shown at 25 to provide attachment means for the hooked end of the spring 22 and at the same time perforations are provided through the washer to 75 permit the passage of the oil.

The spring 22 is a tensed spring and acts constantly to pull the cap 14 down on the cup. The ball 18 seats in the aperture 19 of the piston 8 and holds the same at a constant point in the cup spaced from the top 14 by means of the link 17 and preventing flow of the oil through the opening 19.

In filling the cup the cap 8 is raised against the force of the spring 22 sufficiently to permit a lateral movement and the opening of the top of the cup for the introduction of oil. At the same time the ball 18 moves upwardly and permits the piston 8 together with the membrane 9 to rise 85 under the action of the spring 12. The upward movement of the piston is not sufficient to reengage the opening 19 with the ball 18 and consequently when oil is introduced, it passes freely below the piston and membrane. After introduction of the oil, the cap 14 is replaced, the ball 18 reengages with the opening 19 of the piston 8, thus preventing a free flow of oil through said opening and retaining in the base of the cup substantially all of the oil below the piston and membrane. The spring 22 then acts to draw downwardly the piston and membrane 9, together with the cap 14. In this downward movement, the membrane 9 prevents 100 any free flow of oil from the base of the cup through the piston and the oil is consequently forcibly ejected from the base of the cup into the bearing. It is thus apparent that in this movement the piston 8 together with the membrane 9 act together 105

110 in the manner of a solid plunger when sub-

- jected to a relatively rapid downward movement. The oil contained above the piston 8 may, however, seep slowly through the opening 10, containing the wick 11, if desired, and the membrane 9, the latter alone being sufficient in many cases for preventing a rapid flow of oil from the top of the piston to the base of the cup. It is thus apparent that means are provided, not only 10 for forcibly ejecting oil contained in the cup into the bearing to which the cup is applied, but also for the gradual flow of oil from a reservoir contained within said cup to the bearing.
- 15 The swivel mounting of the end of the spring 22 freely permits of any rotary movement to which the cap 14 may be subjected during handling.

It is readily apparent that the present invention may be embodied in forms of structure differing from that presented in the accompanying drawings which, however, present the preferred embodiment.

We claim as our invention:

- 25 1. An oil-cup comprising a body portion having an oil exit therefrom, a perforated piston movable therein, means for effecting downward movement of the piston and a permeable membrane coöperating with said piston and preventing passage of oil therethrough on downward movement thereof.
- 30 2. An oil-cup comprising a body portion, a cap fitted thereto, a piston movable in said body portion, resilient means acting on said cap and piston and tending to force them toward the bottom of the cup, said means permitting independent movement of said piston when said cap is raised.
- 35 3. An oil-cup comprising a body portion, a cap fitted thereto, a piston movable in said body portion, an opening in said piston, a ball adapted to close said opening, a link connecting said ball to the cap and a tensed spring below said piston and attached to said ball.
- 40 4. An oil-cup comprising a body portion, a cap fitted thereto, a piston movable therein, said piston being provided with an opening, a ball adapted to close said opening, a link connecting said ball to the cap, a tensed spring below said piston and attached to

said ball, and a coiled spring below said piston and tending to force the same upwardly.

5. An oil-cup comprising a body portion, a nipple attached thereto, a cap fitted to said body portion, a piston movable within said body portion, a tensed spring extending within said nipple and acting upon said cap and piston and swivel means retaining said spring within said nipple.

6. An oil-cup comprising a body portion, a nipple attached thereto, a cap fitted to said body portion, a piston movable within said body portion, a tensed spring extending within said nipple and acting upon said cap and piston, a rotatable perforated washer seated in said nipple and means for attaching said spring to said washer.

7. An oil-cup comprising a body portion, a nipple attached to one end thereof, a cap fitting over the other end of said body portion, a centrally bored, perforated plunger movable within said body portion, a centrally-bored permeable membrane below said piston and movable within said body portion, a coiled spring below said permeable membrane and acting to force said membrane and piston outwardly, a swivelly mounted, tensed spring extending within the bore of the nipple, a ball attached to said spring and normally engaging the opening in said piston to close the same, and a link attached to said ball and to the cap.

8. An oil cup comprising a body portion having an oil exit therefrom, a piston movable therein and provided with an aperture permitting the flow of oil through said piston, and means coöperating with said piston to permit gradual flow of oil through the opening therein when at rest and preventing passage of oil therethrough on downward movement of the piston.

9. An oil cup comprising a body portion having an oil exit therefrom, a cap fitted thereto, a piston movable in said body portion, a valve coöperating with the piston, and means connecting the valve and cap whereby on opening the latter the valve is opened and oil is permitted to flow freely through the piston.
